H. R. McCUNE

BRICK MAKING MACHINE

Filed June 25, 1924

INVENTOR.

Herbert R. McCune
Chairman

UNITED STATES PATENT OFFICE.

HERBERT R. McCUNE, OF DECATUR, ILLINOIS, ASSIGNOR TO DECATUR BRICK MFG. CO., OF DECATUR, ILLINOIS, A CORPORATION OF ILLINOIS.

BRICK-MAKING MACHINE.

Application filed June 25, 1924. Serial No. 722,267.

This invention has reference to new and useful improvements in brick making machines, and it has for its principal object to improve and make more sensitive and flexible machines constructed in accordance with the disclosure in Letters Patent issued to me May 13, 1919, No. 1,303,344, and Letters Patent issued to E. D. Mattes June 27, 1916, No. 1,188,670, and other machines of like character, and thereby produce more perfect and uniform bricks.

The machines of the patents to which reference has been made are adapted to produce brick with roughened surfaces, known as "mat" brick, but having the edge portions of these surfaces adjacent the corners of the brick smooth, for the purpose of providing a brick of more attractive and finished appearance and to prevent the chipping or mutilation of these edges.

In the manufacture of "mat" brick having the edge portions of the "mat" surfaces adjacent the corners of the brick smooth, I have found that troweling or tooling the edges of the column of clay as it passes through the die and then subsequently forming or producing the ornamental or "mat" surfaces thereon and cutting the column into brick units does not produce as finely finished and uniform corners of the "mat" surfaces, as is desired, and as may be produced by giving a preliminary formation to the edge portions adjacent the corners of the "mat" surfaces within the forming die, and following the ornamenting of the surface or surfaces of the brick, to provide means to finish such smooth edge portions. This is to some extent due to the fact that the column of clay at times will swell and again deflect in size, and therefore by preliminarily forming the smooth edges within the die and finishing such surfaces after the ornamenting step I am enabled to provide surface finishing means which is self adjustable to the swelling or deflecting or irregularities in the clay column.

That the invention may be more fully understood, reference is had to the accompanying drawing forming a part of the description, illustrating a preferred embodiment of the invention, in which:—

Figure 1 represents a top plan view, in dotted outline, of a brick machine constructed according to the disclosures in the pat-

ents referred to and showing in full lines 55 my improved troweling or finishing tools applied thereto;

Figure 2 is a detail in elevation of one of the finishing tools for the upper edges of the clay column;

Figure 3 is a detail in section as the same would appear on the line 3—3 Figure 2;

Figure 4 is a detail in section as the same would appear on the line 4—4 Figure 2;

Figure 5 is a perspective view of the 65 trowel or tool used in connection with the appliance shown in Figure 2;

Figure 6 shows in plan and in side elevation a form of trowel or tool for the finishing of the brick edges opposite those produced by the tool shown in Figures 2 and 5, and

Figure 7 is a perspective view of one end of a brick produced by my improved mechanism.

Like characters of reference denote corresponding parts throughout the figures.

In Figure 1 for the purpose of differentiating what is old and what is new I have shown in dotted lines those elements of the mechanism known to the art and in full lines the tools and appliances new to the art and embodying my invention. Reference may be had to the patents hereinabove mentioned for a more detailed understanding of these machines or mechanisms, if desired.

Referring to those elements of structure now well known 1 designates the mouth and die of a "stiff mud" press of standard form within which is preferably arranged, although not shown, pressure members to preliminarily form or produce smooth edge portions on both sides of the upper corner edges of a clay column and the smooth edge portion along one side of the lower corner edges of such clay column, of that character shown in the finished article in Figure 7. Reference may be had to Patent No. 1,188,670 for one form of pressure members for producing the preliminary smooth edge portions of the column of clay or bricks, although others may be employed.

2 designates ornamenting means for the sides of the column of clay, as it passes from the die to the usual conveyer mechanism 3. Such ornamenting means being preferably revoluble brush members and the conveying mechanism being preferably an endless

belt. 4 designates an ornamenting means for the top face of the column of clay, which forms the face of the completed brick and such ornamenting means also preferably 5 takes the form of a revoluble brush. These brushes and belt are suitably mounted and driven by suitable mechanism, such for instance as may be seen in Patent No. 1,303,344. Beyond the conveying means or belt 10 3 is located the usual cutters 5 preferably comprising a reciprocal supporting means and a plurality of cutting means for simultaneously severing from the clay column a plurality of brick units. These last mentioned elements are well known to those skilled in the art and it is not thought necessary to further detail the same.

In the machine shown the clay is first passed through the die to form the column 20 into desired shape and by means of certain pressure members do the preliminary work in smoothing the edges of the surfaces to be ornamented. Subsequently the sides of the column are ornamented, following which the 25 top face of the column is also ornamented and then by means of suitable cutters said column is cut into units of brick.

In the improvement disclosed herein I am to use the pressure members heretofore 30 used in the die 1 for preliminarily forming or producing the smooth edge portions *a* and *b* of the surfaces *c* and *d* to be ornamented and then following the last ornamenting set of the surfaces of the clay column, to complete with suitable tools the smooth surfaces *a* and *b*. It has been found in practice that due to the swelling and delection in size of the clay column the initial forming of the smooth corners or edges will not always remain in a finely finished state, if subsequently ornamented, and that the ornamenting step, if there is any deflection or irregularities in the clay column will destroy the effectiveness and finished appearances of such 45 smooth surfaces. Therefore, to produce a more perfect and finely finished article I provide finishing tools for completing or finishing the smooth surfaces *a* and *b* at the edges or corners of the ornamented surfaces, 50 subsequent to the ornamenting step, and I preferably finish the smooth surfaces *a* subsequent to the ornamenting step and prior to the cutting of the column of clay into units of brick, and also preferably finish the 55 smooth surfaces *b* subsequent to the cutting of the column of clay into units of brick, and I have found the placing and operation of such tools most effective in producing a finely finished article.

60 The appliance for trowelling or tooling the edges of the clay column to finish the smooth corners *a* of the ornamented surfaces *c* and *d* is best seen in Figures 2 to 5, both inclusive, although the application and 65 usefulness of such appliance is best seen in

Figure 1, where the same is arranged in duplicate and supported to act on the upper opposite edges of the clay column to produce the finished smooth surfaces adjacent the edges of the top and side ornamented 70 surfaces *c* and *d* of the clay column, subsequent to the last ornamenting step. Such appliance comprises a casting 6 adapted to be secured to a suitable part of the machine and having a socket 7 in which is vertically 75 adjustable a post 8, and provided with a clamp 9 to hold the post in different adjusted positions, whereby to position the height of the trowel or finishing tool for the proper tooling of the ornamented surfaces adjacent 80 the edge of the column of clay. The upper end of the post is provided with transverse openings 10 and 11, the latter threaded to receive a locking clamp 12 to secure an angular shaped threaded rod 13 in position on the post; said rod arranged for adjustment by means of an adjusting nut 14 threaded onto the rod 13. The opposite end of the rod is formed or provided with a bifurcated or 85 split portion 15 the inner faces of which have semispherical seats 16 to receive a ball 17 and provide a ball and socket connection between said rod 13 and a clamp member 18 of which said ball preferably forms an integral part. The split portions 15 of the rod 13 may be caused to firmly clamp the ball 17 and hold the clamp member 18 in adjusted positions by screwing up the screw 19 connecting said split portions 15. The clamp member 18 is formed or provided with a split portion 20 and a depending part 21 thereof and between said split portion 20 is pivoted for adjustment a tool carrying arm or bar 22. In the depending part 21 of the clamp is arranged a spring 100 105 23 bearing against the extreme inner end of said tool carrying arm or bar, the tension of which may be adjusted by means of the set screw 24. The limit of movement of the tool carrying end of the arm 22 in one direction 110 is determined by a stop 25 located in the split portion 20 of the clamp member 18, with which the inner end of said arm 22 engages, but has flexible movement in the other direction due to the spring 23, which 115 will permit the tool to follow the edge of the column of clay in the event of any delections or irregularities therein. The finishing trowel or tool itself, is preferably a small steel angle plate 26 secured by an adjusting 120 screw 27 to the tooling end of the arm or bar 22 which will allow for resting said trowel or tool 26 in proper position on the edge of the clay column. This tool 26 acts to put a very decidedly finished effect on the 125 column of clay completing the smooth surfaces *a* for the top and side ornamented surfaces at the edges preliminarily started by the pressure members, not shown, in the die 1. As illustrated, the appliance for the 130

finishing tool 26 is adjustable to meet varying conditions and is flexible, therefore sensitive to the conditions of the clay, resulting in the production of finely finished and uniform smooth corners *a* on the finished ornamented brick units.

The appliance for producing the finished smooth surface *b* at the opposite edge of the side surface *d* is arranged in duplicate and supported to act on the lower edges of the clay column, preferably after the same has been severed into units of brick, to produce the finished smooth surfaces adjacent the lower edges of the ornamented side surfaces

d. Such appliance comprises a plate 27' adapted to be supported on or secured to a suitable part of the machine and to said plate is pivotally connected a curved trowelling or finishing tool 28, which is normally held in its operative or active position by means of a spring 29 bearing thereagainst and adjustably connected at its opposite end to the plate 27', by the adjusting screw 30.

By means of the adjusting screw and the spring proper tension on the trowel or tool 28 may be had in order that the proper results may be obtained in the operation of this appliance. While I prefer to locate the tools 28 at a point beyond the cutting off of the units of brick and am of the opinion that the best results may be obtained by so placing the same they could be placed, with some modifications, between the tools 26 and the cutters.

I have used the expression "mat" brick for textured bricks in general, more specifically because of its use in the patents referred to to define textured brick, and I wish it understood that the use of the word "mat" is not limited to special means of forming textured brick, but to textured brick generally.

What I claim is:—

1. In a brick making machine, in combination with a die for shaping a column of clay, surface ornamenting means, cutters

for severing the column into units of brick and means for preliminarily smoothing edge portions of the surfaces to be ornamented and prior to such ornamentation, of finishing tools arranged on either side of the path of travel of the column of clay adapted to finish the smooth edge portions of adjacent ornamented surfaces after the ornamenting step and before severing the column into units of brick, adjustable and flexible supports for said tools for aligning the tools in relation to the travel of the column of clay and for self adjustment of the tools whereby the same may accommodate themselves to deflections or irregularities in the column of clay, and other finishing tools arranged on either side of the path of travel of the severed bricks adapted to finish the smooth edge portions of the corners of the ornamented sides of the brick units, after the severance of said brick units from the column, and yieldable pressure means for said last mentioned tools.

2. In a brick making machine, in combination with a die for forming a column of clay, surface ornamenting means and cutters for severing the ornamented column into units of brick, of tools comprising angular shaped plates for smoothing the edges of adjacent ornamented surfaces, adjustable and flexible supports for said tools, other tools comprising blades for smoothing opposite edges of certain of said ornamented surfaces, supports for said blades, and yieldable pressure means for said blades.

3. An attachment for brick making machines, for smoothing the edges of adjacent ornamented surfaces, comprising an angular shaped tool, and support for said tool including a plurality of members adjustably and flexibly connected, whereby such tool may be adjusted to different angular positions.

In witness whereof, I have hereunto affixed my hand this 19th day of June, 1924.

HERBERT R. McCUNE.
